[57] CLAIM

The ornamental design for a safety fuel-dispensing bottle cap, as shown and described.

DESCRIPTION

FIG. 1 is a perspective view of a safety fuel-dispensing bottle cap showing my new design;

FIG. 2 is a top plan view thereof;

FIG. 3 is a bottom plan view thereof;

FIG. 4 is a right side elevational view thereof, the left side view being a mirror image of that shown; and,

FIG. 5 is a front elevational view thereof.
